BATTERY-OPERATED POWER HANDLE FOR A
TOOTHBRUSH, MANICURE IMPLEMENT OR
SIMILAR ARTICLE

Arnold M. Thompson, Wheaton, Ill., assignor to Thompson Designs, Inc., Addison, Ill., a corporation of Illinois

Filed July 1, 1963, Ser. No. 75,596

Term of patent 14 years

(Cl. D9—2)

FIG. 1

FIG. 3

FIG. 4

FIG. 2

FIG. 5

FIG. 6

FIG. 1 is a top perspective view of a battery-operated powerhandle for a toothbrush, manicure implement or similar article embodying my design;

FIG. 2 is a side elevational view;

FIG. 3 is a rear elevational view;

FIG. 4 is a front elevational view;

FIG. 5 is a top plan view; and

FIG. 6 is a bottom plan view.

I claim:

The ornamental design for a battery-operated powerhandle for a toothbrush, manicure implement or similar article, substantially as shown.
